Primary Examiner — Rebecca Tsehay(74) *Attorney, Agent, or Firm* — Lee Sullivan Shea & Smith LLP(57) **CLAIM**

The ornamental design for a vape machine, as shown and described.

DESCRIPTION

FIG. 1 is a bottom perspective view of a vape machine, according to my new design;

FIG. 2 is a top perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof; and,

FIG. 8 is a rear view thereof.

The broken lines in the drawings depict portions of the vape machine that form no part of the claimed design.
